Fig. 2.

Fig. 3.

Fig. 4.

FIG. 5.FIG. 6.FIG. 1 is a perspective view of a single panel of the panel unit shown in FIG. 2;

FIG. 2 is a perspective view of a panel unit showing our new design, the broken lines showing of the door frame being disclosed for illustrative purposes only, it being understood that the pattern shown repeats throughout the panel;

FIG. 3 is a sectional view taken on line 3—3 of FIG. 2;

FIG. 4 is a fragmentary enlarged view showing the detailed shape of the central portion of the panel in FIG. 1;

FIG. 5 is a perspective view of a modified form of the panel unit shown in FIG. 2, the broken line showing of the door frame being disclosed for illustrative purposes only;

FIG. 6 is a sectional view taken on line 6—6 of FIG. 5; and

FIG. 7 is a sectional view taken on line 7—7 of FIG. 1. The characteristic features of the design reside in the surface ornamentation. The rear of the unit is plain.

We claim:

The ornamental design for a panel unit substantially as shown and described.
